OILING RING

Frederick W. Esch, Indianapolis, Ind.

Application June 27, 1938, Serial No. 216,161

4 Claims. (Cl. 308—129)

This invention relates to an oiling device and particularly to that type of oilers in which an oiling ring is carried loosely over a shaft to be revolved thereby in order to lift oil from a lower reservoir and carry the oil up on the ring into contact with the shaft at a shaft bearing. The invention resides particularly in the means for forming the ring in parts and securing the parts one to the other so as to present a durable structure which will not work loose nor ride on the shaft in a fixed position. Further objects and advantages of the invention such as cheapness in cost of manufacture, durability, and ease of assembly, will become apparent to those versed in the art in the following description of the invention as illustrated in the accompanying drawing, in which

Fig. 1 is a section through a bearing showing the invention applied thereto;
 20 Fig. 2, a ring blank partially formed in side elevation;
 Fig. 3, the formed blank in top plan view;
 Fig. 4, a side elevation of the ring in finished form;
 25 Fig. 5, a bottom plan view of the ring on an enlarged scale and in partial section; and
 Fig. 6, a detail in top plan view of a modified form of joint.

Like characters of reference indicate like parts throughout the several views in the drawing.

Referring first to Figs. 2 and 3, a blank ring preferably having a rectangular cross section is initially formed to have circular end portions 10 and 11 with interconnecting straight portions 12 and 13. The lengths of the straight portions 12 and 13 are made to be such that when in the finished assembled ring, that ring will be completely circular as will hereinafter appear.

These flat portions 12 and 13 are cut and shaped to have the configurations as indicated in Fig. 3 wherein opposing lips 14 and 15 are presented with their under faces cut back on angles, preferably 45 degrees and the material is removed between these lips 14 and 15 for a distance in from the face A of the blank. This removed portion leaves a slot across the face of the ring on each of the flat portions 12 and 13. In the bottom of this slot are cut a number of teeth 16 on the side adjacent the lip 14 and 17 on the other side adjacent the lip 15 with a deeper portion of the slot extending across the flat portions centrally of the space between the lips 14 and 15 and between the sets of teeth 16 and 17 as indicated in Fig. 3. The height of the teeth 16 and 17 in relation to their root and outside terminating end planes is made to be such that equal portions of the teeth lie on each side of the central plane midway between the faces A and B of the blank. The shape of the teeth 16 and 17 may assume a number of forms, one particular form working to ad-

vantage is the square tooth as herein indicated. Also the number of teeth in each set while necessarily being identical may vary from one or more as may be desired and particularly depending upon the size of the ring being made, more teeth being desired with larger rings than in smaller rings.

The foregoing operations of forming the lips 14 and 15 and the teeth 16 and 17 have been made in the ring downwardly from the face A. Another 10 operation is performed on the ring blank from the face B which consists of cutting a 90 degree groove 18 across each of the portions 12 and 13 on their face B sides, these grooves being centered transversely across the rings in relation to the spacing 15 between the ends of the lips 14 and 15. This notch 18 is cut sufficiently deep as will just sever the blank into the two portions 10 and 11. Thus the blank is formed into two identically shaped portions 10 and 11 separated one from the other. 20 One of these portions is reversed end for end in relation to the other portion. For example, when the two portions 10 and 11 are just cut through, Fig. 2, there are left the free ends C and D on the portion 10 and E and F on the portion 11. 25

Then in order to assemble the two portions 10 and 11, the portion 10 is held in its original position as indicated in Figs. 2 and 3 to bring the ends F and E into juxtaposition with the ends C and D respectively. In bringing these ends one toward 30 the other, the end C is brought above end F and likewise the end D is brought above the end F and the two parts pushed in parallel alignment one in relation to the other so as to bring respective end portions under respective lip portions 35 with the respective teeth 16 and 17 sliding into mesh end to end. In other words, one ring portion is moved in relation to the other as suggested in Fig. 4 in moving the ring portion 10 relatively from the dash line position to the solid line position 40 in relation to the ring portion 11. When these two portions are thus brought together to form one continuous ring in effect, they are preferably locked in some such manner as by soldering or by employing screws 19 and 20 screwthreadedly 45 interengaging the two ring portions, Fig. 5.

In order to secure this particular means for interengaging the ends of the ring portions, the slope of the sides of the notch 18, Fig. 3, must be identical with that of the under sides of the lips 14 and 15 since these faces of the notch 18 are the ones that set against the under faces of the lips 14 and 15. Likewise the teeth 16 and 17 must be cut in that relation, one set with the other, as will permit the intermeshing from their ends 50 when the rings are placed in position one in respect to the other as above indicated. By reason of these interlocking teeth 16 and 17 the ring portions cannot pull apart one from the other circumferentially and by reason of the ends lap- 55 60

ping under the lips 14 and 15, the ring portions cannot be displaced one from the other laterally and the only permissible movement is that chordal movement as suggested in Fig. 4, but this one line of movement is prevented by reason of the interlocking means such as the screw suggested.

This particular assembly gives a very effective locked ring that will not work loose in operation regardless of the severity of vibration or speed.

10 of the shaft 21 which may carry the finished ring. However, in some installations, it may be difficult to assemble the two portions of the ring about the shaft 21 due to limited space and for such cases, the type of joint as indicated in Fig. 6 may 15 be employed. In this form, not only are the lips 14 and 15 undercut on 45 degree angles as are the respective end portions of the ring segments, but the teeth 22 and 23 are likewise cut to have 45 degree sloped faces so that the ring segments may 20 be brought to alignment end to end to have the end G, for example, initially abut the end of the lip 14 and thereby be carried down the 45 degree slope to bring all of the other elements into alignment, this being permissible since all of the faces 25 of the teeth and of the ends and lips are cut in respective parallel planes permitting and directing the final intimate contact therebetween, this movement being suggested by the initial dash line position of the one segment progressing to the 30 solid line position, Fig. 6. It is understood of course that in this form, Fig. 6, the various elements such as the lips and teeth are cut in the respective ends in identical relationship one with the other in respect to the central longitudinal 35 plane through the ring. This form may likewise be locked together in any one of many ways, one particular way being by means of a screw inter-engaging the two ends to prevent their shifting.

It is to be understood that the two ring portions are semi-circular with the inner ends of the 40 flat portions 12 and 13 joining the portions on the diametrical lines of the curved portions. Then when the ring portions are assembled to form the complete ring, the inner periphery of the ring approaches very nearly a true circle. In fact, the periphery is brought to a true circle by a slight cut taken over the periphery after assembly.

In reference to that type of ring segment joint 45 shown in Figs. 1-5, the undercutting of the lips 14 and 15 may be tapered slightly across the segments, so that as in Fig. 4, the upper ring segments end may be freely entered down on the other and then the two ends forced and wedged home to the continuous periphery positions. In 50 this manner, a secure interlocking is had without use of the screw 20.

While I have herein shown and described my invention in the best form now known to me, it is 55 obvious that structural changes may be employed without departing from the spirit of the invention such as change in slope of the faces of the teeth and lips and segment ends, and I therefore do not desire to be limited to that precise form beyond the limitations as may be imposed by the following claims.

I claim:

1. A two piece oiling ring formed of symmetrical parts, each part comprising a semi-circular open end portion terminating with short connecting ends, each end being formed to have a notch cut back from the terminal end to leave an under-

5 cut shoulder at the inner end of the notch, at least two grooves formed transversely across the notch face to define a tooth thereacross, and each end being bevelled on its side opposite said notch to a slope conforming to that of the undercut face of said shoulder, said ring parts being assembled to have the bevelled end of one portion engaged under the shoulder of the other and said teeth meshed one between the others.

2. A two piece oiling ring formed of symmetrical parts, each part comprising a semi-circular open end portion terminating with short connecting ends, each end being formed to have a notch cut back from the terminal end to leave an undercut shoulder at the inner end of the notch, at 15 least two grooves formed transversely across the notch face to define a tooth thereacross, and each end being bevelled on its side opposite said notch to a slope conforming to that of the undercut face of said shoulder, said ring parts being assembled to have the bevelled end of one portion engaged under the shoulder of the other and said teeth meshed one between the others, said notch in each end being at the juncture between the circular and straight portions of the ring parts 20 whereby, upon assembly, a substantially complete circular inner periphery is formed, said grooves being parallel to the diameter of the assembled ring.

3. A two piece oiling ring formed of symmetrical parts, each part comprising a semi-circular open end portion terminating with short straight ends, each end being formed to have a notch cut back from the terminal end to leave an undercut shoulder at the inner end of the notch, at least 35 two grooves formed transversely across the notch face to define a tooth thereacross, and each end being bevelled on its side opposite said notch to a slope conforming to that of the undercut face of said shoulder, said ring parts being assembled to have the bevelled end of one portion engaged under the shoulder of the other and said teeth meshed one between the others, said notches and 40 said grooves being formed to have forty-five degree slopes, whereby the ring parts may be moved 45 into assembly by pushing the ends of one part along over the ends of the other part normally of the diameter of the finished ring to cause the slopes of the undercut notch ends to direct the ends laterally one against the other into snug 50 seating arrangement to form a continuous ring without offsets at the part junctures.

4. A two piece oiling ring formed of symmetrical parts, each part comprising a semi-circular open end portion terminating with short connecting ends, each end being formed to have a notch cut back from the terminal end to leave an undercut shoulder at the inner end of the notch, at 55 least two grooves formed transversely across the notch face to define a tooth thereacross, and each end being bevelled on its side opposite said notch to a slope conforming to that of the undercut face of said shoulder, said ring parts being assembled to have the bevelled end of one portion engaged under the shoulder of the other and said teeth meshed one between the others, the undercut 60 faces of said shoulders being tapered in each instance inwardly and toward the opposing shoulder, whereby the two parts may be seated in 65 wedging engagement.
